TINSEL GARLAND

Filed May 28, 1929

UNITED STATES PATENT OFFICE

BERNARD E. FRANKE, OF CATONSVILLE, MARYLAND

TINSEL GARLAND

Application filed May 28, 1929. Serial No. 366,576.

The invention relates to a tinsel ornament known to the trade as tinsel garland, the same being used as a Christmas decoration on Christmas trees and for shop windows, 5 Christmas gardens and the like and for other decorative purposes. As now in use, this consists of a core or cord which is ordinarily of cotton or other suitable material composed of several strands with which transverse strips 10 of tinsel are interwoven. These tinsel strips, which are ordinarily about an inch long, project radially in all directions from the cord, the bright tinsel strips giving the effect of a tinsel brush which ordinarily is about an 15 inch in diameter and of indefinite length.

This product, known as tinsel garland, as at present made and offered for sale, is of reduced luminosity on account of the non-reflecting nature of the core or cord which, 20 being opaque, absorbs and diffuses instead of reflecting the rays of light which come in contact with it. In addition to the general effect of low luminosity resulting from the nature of the central cord or strand, this cord 25 becomes under certain lighting conditions and from certain viewpoints, most objectionably prominent in its contrast with the tinsel on account of its lack of lustre.

The object of the present invention is to increase the luminosity of the garland and reduce the prominence of the cord or core of textile or similar fibre by giving it a reflecting surface of an appearance similar to that of the tinsel strips and of substantially equal 35 lustre.

In the accompanying drawing I have illustrated a tinsel garland embodying the invention in the preferred form.

In the drawings: 40 Figure 1 is an elevation of a short section of tinsel garland looking at the same at right angles to the axis, i. e., to the length.

Figure 2 is a similar elevation of a short length of the garland shown on an enlarged scale, the tinsel strips being omitted from the lower end of the core or cord forming the center, and the extreme end of the core being shown as unravelled to illustrate the individual strands which are in turn partially 45 unravelled at their ends, the outer radial ends

of the tinsel strips being broken away for convenience of illustration.

Figure 3 is an elevation of one of these strands ready to be used in the manufacture of the garland, the same being shown on a 55 scale corresponding to Figure 2.

Figure 4 is a transverse section through the same on line 4—4 of Figure 3.

Referring to the drawings by numerals, each of which is used to indicate the same 60 or similar parts in the different figures, the construction shown comprises a short section of tinsel garland indicated in a general way by reference character 1. This garland consists of a central cord or core 2 and transverse 65 substantially radial or diametrical tinsel strips 3, which are interwoven at their centers with the strands 4 of the cord, so that the end portions 5 of the strips 3 on each side of the center project on all sides of the core 70 to cord 2 in substantially radial directions, giving the effect of a tinsel brush or garland of indefinite length, and in accordance with the usual commercial practice about an inch in diameter, although the exact diameter is 75 immaterial. The garland as thus described is a regular well known commercial product of some years standing.

On account of the lack of lustre of the central core or cord 2, which is opaque and otherwise of a light absorbing and diffusing nature, this cord is unduly conspicuous, greatly reducing the total or apparent luminosity of the tinsel, particularly when it appears in a mass of several lengths of the garland laid 85 together or superimposed. This effect is most conspicuous at certain angles in which the tinsel strips are seen from the ends or edges instead of from the flat sides.

To overcome this difficulty and reduce the 90 light diffusing and absorbing effect of the central core or cord, the applicant has devised an economical and effective method of covering and concealing the cord by imparting to it substantially the same reflecting 95 properties as are possessed by the tinsel strips.

In the preferred form of the invention, this is accomplished by wrapping each of the individual strands 4 with a strip of tinsel 6 as 100 best illustrated in Figure 3 which shows the

strand partly unravelled and the strip 6 unwound at the end and projecting. It is, of course, apparent that in the broad conception of the invention the exact method of wrapping the strand or the exact method of applying the tinsel to the core is not essential. In accordance with the form shown, the strands 4 are then twisted or braided to form the central cord or core 2, these strands being in the form of the invention shown six in number, although the exact number of strands is not, of course, of importance. In accordance with the prevailing commercial practice, the tinsel strips are affixed to the core by placing them between the strands as the latter are twisted or braided into the core, the tinsel strips being thus interwoven with the strands and extending transversely in relation thereto, their ends projecting radially on all sides of the core.

In this way or in any convenient manner, the core is completely covered with tinsel which in no wise interferes with the radially placed tinsel strips 3 and in such a manner that the textile fibre composing the core is completely concealed, giving to the garland a 100 per cent radiating surface instead of 75 or 80 per cent as in the previous commercial product. In the form shown the cord or core is wrapped externally with a wire or wires 7, preferably of bright metal, which increase the strength and durability of the construction and tend to prevent kinking, holding the garland in the position and contour in which it is placed.

In the new garland the central core becomes inconspicuous and when it can be distinguished, its surface so closely resembles the remainder of the garland as to be in no wise objectionable.

I have thus described specifically and in detail a tinsel garland product embodying the feature of my invention in the preferred form in order that the manner of constructing, applying and using the product of the invention may be fully understood, however, the specific terms herein are used descriptively rather than in a limiting sense, the scope of the invention being defined by the claims.

What I claim as new and desire to secure by Letters Patent is:

1. A tinsel garland consisting of a flexible central core of textile material, transverse tinsel strips and tinsel covering the core.
2. A tinsel garland consisting of a central core of textile fibre and transverse tinsel strips, tinsel covering the core, said covering being interwoven with the textile material forming the core.
3. A tinsel garland consisting of a central cord or core, of textile fibre, strands composing said core, said strands being covered with tinsel and tinsel strips extending transversely of the core and projecting therefrom, said strips being interwoven with the strands.

4. A tinsel garland consisting of a core and tinsel strips extending transversely of the core and projecting therefrom at their ends, the core being composed of strands, each individual strand being wrapped with tinsel.

Signed by me at Catonsville, Baltimore County, Maryland, this 27th day of May, 1929.

BERNARD E. FRANKE.
